DRAINBOARD GUARD

Steven Chambers, New York, N. Y., assignor of
one-half to Jerome J. Kern, New York, N. Y.

Application July 12, 1940, Serial No. 345,026

2 Claims. (Cl. 141—11)

The present invention relates to a guard for drain boards and the like, and more particularly to a guard for sink boards which will prevent dishes from sliding or falling therefrom.

One of the objects of the invention is to provide a drain board attachment of the character indicated which is simple in construction, economical in production and practical in application.

Another object is to provide a guard which can be readily and firmly attached to sinks now generally in use and which can be easily removed therefrom for the purpose of cleaning the sink board.

Still another object is to provide a guard for drain boards and the like which can be adjusted to different sizes.

Still a further object is to provide a guard of the character indicated which will not damage or chip dishes resting or sliding against it and which has an attractive appearance and, at the same time, is strong and durable.

Other objects and advantages inherent in the invention will become apparent from the following detailed specification and accompanying drawings which describe and illustrate the preferred embodiment of the invention, together with modifications thereof.

In the drawings:

Figure 1 is a perspective view of a sink board guard, according to the invention.

Figure 2 is a cross-section of the rods of which the sink board guard, shown in Figure 1, is composed.

Figure 3 is a front elevation partly in section showing the guard applied to the sink.

Figure 4 is a perspective view of a modification.

Figure 5 is a perspective view of another modification.

Throughout the drawings, similar reference characters represent corresponding parts.

Referring in greater detail to the drawings, the guard is composed of a plurality of longitudinal rods 10 and transverse members 11 which thus form a grill. These rods are formed of a metal or heavy wire core 12 and are covered by a resilient coating of rubber or similar material 13.

The grill thus formed provides a comparatively stiff guard or rim. This guard or rim is bent to conform to the contour of the drain board to provide a front portion 14 and side portions 15 and 16.

The transverse rods 11, composing the grill work of the front portion 14, are longer than the

remaining other transverse rods 11 and extend a substantial distance below the lowermost of the rods 10.

These rods are then bent upwardly in a W fashion to fit over the partition 17 of the sink. The ends of the rods are preferably bent upwardly again and connected by a longitudinal rod 18.

As will appear from the drawings, this rod 18 is spaced from the U bends of the rods as well as from the partition 17, and may be used as a handle in removing the guard from the partition 17.

The two end rods of the front portion 14 preferably extend further below the grill work frame than the intermediate rods in order to provide a better support against the partition 17.

Similarly, the U bends formed by the end rods extend further down on the opposite side of the partition 17 for the purpose of providing a better grip.

The rods are made of substantially resilient material so that the same may be bent or adjusted to fit the particular partition to which the guard is intended to be applied.

After the guard has been applied to the partition 17, the drain board 19 may be replaced in its proper position resting on top of the partition 17 and the U bends of the transverse front bars 11.

It will be noted that by virtue of the construction described and illustrated, the guard extends a substantial distance below the surface of the drain board and in this manner the dishes placed inside the guard will be prevented from slipping through or falling into the sink.

Figure 4 shows a modification in which there is a telescoping member 20 composed of rods of a construction similar to the main guard. This member telescopes within the sleeves 21 mounted on the main guard.

The ends of the longitudinal rods, composing the adjustable member 20, may be bent upwardly to prevent the rods from pulling out of the sleeves 21.

The flexibility of the guard makes it possible to apply it to various forms and styles of sinks by slight modification of the U bends and bifurcated portion of the guard.

The guard is easily and quickly attached to, or detached from, the partition 17 of the sink, simply by gripping the main rods 10 and the rod 18.

Figure 5 shows a modification similar to Figure 4 in which the telescoping portions 20 are

joined to an end portion 22, making a completely enclosed structure.

It is apparent the specific illustrations above shown have been given by way of illustration and not by way of limitation and that the structures above described are subject to wide variation and modification without departing from the scope or intent of the invention, all of which variations and modifications are to be included within the scope of the present invention.

What is claimed is:

1. A guard for drainboards and the like adapted to be detachably secured to a partition supporting one end of the drainboard, said guard comprising a shield having a front portion and side members extending from said front portion, an attachment portion depending from said front portion, said attachment portion having the

shape of an inverted U for straddling the drainboard partition, said inverted U shaped portion being offset inwardly from said front portion whereby the drainboard will rest upon said inverted U shaped portion.

5 2. A guard for drainboards and the like comprising the combination with a partition supporting one end of the drainboard, said guard comprising a flexible shield for the edges of said drainboard, clamping members depending from said shield member and offset inwardly therefrom, said clamping members being adapted to engage the top surface and sides of said partition whereby the front end of the drainboard will rest upon said clamping members when supported on said partition.

STEVEN CHAMBERS.
